Primary Examiner — Selina Sikder(74) *Attorney, Agent, or Firm* — Muncy, Geissler, Olds & Lowe, P.C.(57) **CLAIM**

The ornamental design for a control panel for bathing robot, as shown and described.

DESCRIPTION

FIG. 1 is a front plan view of the control panel for bathing robot showing our new design;

FIG. 2 is a perspective view thereof; and,

FIG. 3 is an enlarged perspective view of the control panel for bathing robot shown in FIG. 2 view for ease of illustration.

The broken lines showing structural features are for illustrative purposes only and form no part of the claimed design. The dash-dot broken lines define the bounds of the claimed design and form no part thereof.
